DESIGN FOR A COMBINED WALLET AND CARD CASES

George Markus, New York, N. Y.

Application December 29, 1944, Serial No. 117,146

Term of patent 7 years

(Cl. D87—3)

To all whom it may concern:

Be it known that I, George Markus, a citizen of the United States of America, and residing in New York city, New York, have invented a new, original and ornamental Design for a Combined Wallet and Card Cases, of which the following is a specification, reference being had to the accompanying drawing, forming part thereof.

Figure 1 is a top plan view of the combined wallet and card cases showing my new design with the card case compartment in open position. The opposite side of the wallet is substantially plain.

Figure 2 is an edge view of the combined wallet and card cases with the card case compartment closed and turned downwardly, and

Figure 3 is a top plan view, similar to that of Figure 1, but on a smaller scale and showing the card case compartment closed.

I claim:

The ornamental design for a combined wallet and card cases, as shown and described.

GEORGE MARKUS.
